CORE FORMING DEVICE

Edmund P. Kinne and Len T. May, Alliance,
Ohio, assignors to American Steel Foundries,
Chicago, Ill., a corporation of New Jersey

Application December 26, 1931
Serial No. 583,306

35 Claims. (Cl. 22—10)

The present invention relates to core forming devices, and more in particular to novel means for forming journal box cores.

Among the objects of the present invention is 5 to provide a core forming device adapted to be easily manipulated for forming or fashioning journal box cores, the same including means whereby each part of the journal box may be easily and readily formed without resorting to 10 hand operations.

At the present time journal box cores and the like are usually rammed by means of an air rammer, this operation requiring considerable skill on the part of the operator to produce satisfactory 15 and uniform cores. When these cores are made in this manner, the core forming box is in an upright position and the top or front of the same is opened to permit ramming. This necessitates hand finishing of the core around the front end, 20 this step making it very difficult to secure a true, uniform shape at this point on the core. Further, the placing of chills at certain locations embedded in the core is also difficult with the present known method of ramming.

25 It is therefore an object of the present invention to provide novel means whereby these journal box cores may be more accurately formed at the important or crucial points.

The present invention also comprehends the 30 idea of providing novel means for mechanically ramming the core in such means in combination with the core forming device requiring less skill and less physical effort on the part of the operator to secure a true, uniform and accurately 35 formed core.

Still another object of the present invention is 40 to provide a novel core forming device including core forming elements so associated and adapted to be operated in such a manner as to speed up this core forming operation, thereby increasing the output, as well as producing a core far superior to anything made in accordance with the present well-known method of making the same.

45 With these and various other objects in view, the invention may consist of certain novel features of construction and operation, as will be more fully described and particularly pointed out in the specification, claims and drawings appended hereto.

In the drawings, which illustrate an embodiment of the device, and wherein like reference characters are used to designate like parts—

55 Figure 1 is a view in end elevation of a core forming device made in accordance with the

present invention and in association with a mechanical ramming device;

Figure 2 is a view in side elevation of the embodiment shown in Figure 1 of the drawings;

Figure 3 is also a view in side elevation disclosing the device in position to be swung into its discharge position;

Figure 4 is a view in side elevation showing the device in its discharge position;

Figure 5 is a top plan view showing the core 65 forming elements in a position whereby the formed core may be removed;

Figure 6 is a view in vertical cross section taken in the planes represented by the line 6—6 in Figure 2 of the drawings;

Figure 7 is a fragmentary view in vertical cross section taken in a plane represented by line 7—7 of Figure 4 of the drawings;

Figure 8 is a fragmentary view in end elevation taken in a plane represented by line 8—8 of Figure 3 of the drawings;

Figure 9 is a fragmentary top plan view of another core forming device made in accordance with the present invention;

Figure 10 is a fragmentary view in side elevation of the device shown in Figure 3 of the drawings, with parts broken away to disclose the construction more in detail; and

Figure 11 is a fragmentary view in side elevation similar to Figure 10 of the drawings, showing the core forming box in an open position.

Referring now more in detail to the drawings, a core forming device made in accordance with the present invention is shown as comprising a base 2 and a core box 4. This core forming box 90 4 includes the relatively movable core forming elements 6 and 8 adapted to form a major portion of the journal box core 10, and a core forming element 12 adapted to close the open end of the core forming elements 6 and 8.

The core forming element 12 is formed with a central lug or ear 14 which is apertured to receive a bolt 16 secured in the ears 18 and 20 provided on the base 2, whereby the core forming box as a whole may be moved from the ramming position shown in Figure 2 of the drawings to its upright or discharging position as shown in Figure 4 of the drawings. The central lug or ear 14 of the core forming element 12 is further provided with an extending part 22 apertured to receive a bolt 24 arranged to extend normal to the core forming element 12. The core forming elements 6 and 8 are provided with the spaced hinges or lugs 26 and 28, respectively, these hinges or lugs being formed integral with the body por- 110

tion of these core forming elements, the same being apertured adjacent their ends for receiving the bolt 24 and for swingably securing these core forming elements thereto.

5 In Figure 2 of the drawings, the core forming box is shown in its ramming position, and at this time, the core forming elements 6 and 8 are swung together and the hinges 26 and 28 thereof are adapted to be received in the depressed portion 30 10 of the base 2. When these elements are in this position, these core forming elements are maintained in their closed position by means of the wedge surfaces 32 and 34 provided on these hinges or lugs which are adapted to cooperate with complementary wedge surfaces provided on the extensions 36 of the base 2, and at 35. The core forming element 12 is also swung into its proper position simultaneously with the movement of the elements 6 and 8 for closing the open end of 20 this core forming box and is secured to the core forming elements 6 and 8, as by means of the wedge lugs 38. The core forming box 4 is locked to the base in this position by means of a latch 40 normally urged into its latching position by 25 means of a coil spring 42 and adapted to engage with a lug or projection 44 provided on each of the core forming elements 6 and 8.

The core formed by the core forming box 4 is supported for removal upon a plate 46 attached 30 to a lifting tool 48, this lifting tool being provided with a collar 50 for holding the same in place relative to the core forming elements 6 and 8 during the ramming operation. This plate 46 is formed with an annular depressed portion 47 35 adapted to be received within an opening 49 of the end element 12 and the same has the flange 51 engaging this element 12 adjacent the opening 49 whereby the plate is held in association therewith. When the core forming box 4 is in the position as shown in Figures 1 and 2, the same is 40 ready to receive the core sand. With this box set as disclosed in these figures, the core sand is delivered into the box through the opening 52 formed in the top of the core forming elements 45 6 and 8. This core sand is directed into this opening by means of a hopper 54 and the hopper is filled to the top in this filling operation. The core forming device as disclosed in these figures is adapted to rest or be mounted upon a jar ramming machine, which may be suitably operated by 50 suitable means for causing a jarring or settling of the same down to a position represented by the line 58 of Figure 1 of the drawings. The hopper 54 is then removed and any sand projecting above 55 the line 58 would be removed by striking the same off. After this operation has been completed, the weight 60 is then applied, as shown in Figure 2 of the drawings, and the jarring or jolting continued until the weight 60 has assumed a position 60 corresponding to that disclosed in Figure 6 of the drawings.

After the core sand has been jarred or jolted so that the same conforms to the core forming surfaces of the elements 6, 8 and 12, the weight 60 65 is removed and a handle or bail 62 is placed along the core forming elements 6 and 8 to hold the same in association during the following steps, as will be later more fully described. This handle or bail 62 is guided in the brackets 64 and 66 and 70 is received within the pockets 68. After these various steps have been effected, the core box 4 is then in condition to be swung around the pivot point 16 into a position for discharge of the formed core. This movement is initiated, upon 75 release of the latch 40, by means of a coil spring

70 which raises the core box 40 slightly above the base 2 so that the same may be easily swung. The core box 4 is then swung about the pivot point 16 and in a clockwise direction, as shown in Figure 4 of the drawings, approximately 90 degrees to a position where the core forming element 12 rests upon the discharge platform 72 made integral with the base 2. When the box is in this position, the handle or bail 62 is removed, and the core forming elements 6 and 8 swung about the pivot point 24 into a position as shown in Figure 5 of the drawings. The core is then ready to be removed and is conveniently carried in this position by means of the lifting tool 48.

In Figures 9 to 11 inclusive is disclosed an alternative core box construction made in accordance with the present invention, the same corresponding essentially with the previously described embodiment. In this alternative arrangement, the core forming box 74 is provided with the relatively movable core forming elements 76 and 78 forming the major portion of the core, the open end of which is closed by the core forming element 80. As in the hereinbefore described core forming device, the core forming element 80 is formed with an apertured lug 82 mounted on the rod or pin 84 journaled in a base 86, whereby the core box as a whole may be rotated from a ramming position, as shown in Figure 10 to an opening position, as shown in Figure 11.

The core forming element 80 is further formed with the extending lug 88 adapted to carry the normally disposed bolt or pin 90, upon which spaced lugs 92 and 94 of the core forming elements 78 and 76, respectively, are mounted, these lugs or hinges cooperating with guide portions on the base 86 in a manner as hereinbefore described for holding these core forming elements in closed position during the ramming operation.

In the present embodiment, the core forming box 74 is swung or rotated as a whole about the pin 84, as by means of a fluid cylinder 96 suitably secured at one end to the base, as by means of the bolt 98, a piston 100 being operable therein and under the action of a compressed fluid. 115 This piston 100 is operatively connected to a lug or hinge element 102, by means of the bolt 104, whereby the core forming box is swung about the pin or bolt 84 into either of the positions shown in Figures 10 and 11.

Associated with the core forming element 80 is a core carrier plate 106 for supporting the core when the same is removed from the core forming box 74, this core carrier plate being held in position and in association with the element 80 during the ramming operation by means of a magnetic device 108. This device comprises a casing or shell 110 which is secured to the element 80, as by means of bolts 112, and which forms a housing for a core 114 about which is wound a coil 116, this core being secured at one end to the casing by the bolt 118 and having its other end protruding into the opening 120 formed in the element 80. The plate 106 is formed with an annular depressed or dished portion 122 adapted to contact with the core 114 whereby the same may be held in association with the element 80 during the ramming operation. As clearly shown in Figures 9 to 11 inclusive, the casing or shell 110 is received in a recess or depression 123 when the core forming box is rotated into a position for removal of the core.

From the above disclosure, it will be clearly apparent that a journal box core made in accordance with the above disclosure requires no hand

- operations, the surfaces thereof being formed mechanically and rapidly, this particular device requiring less skill and less physical effort to be operated, although the core formed thereby is 5 far superior to cores requiring hand forming.
- It is to be understood that we do not wish to be limited by the exact embodiment of the device shown, which is merely by way of illustration and not limitation, as various and other forms of the 10 device will of course be apparent to those skilled in the art without departing from the spirit of the invention or the scope of the claims.
- We claim:
1. A core forming device comprising a base, a core forming box swingably supported on said base, said box including relatively movable core forming elements, and cooperating wedge surfaces on said base and elements for holding said elements together when said box is in position 15 for ramming.
  2. A core forming device comprising a base, a core forming box supported for rotation as a unit upon said base, said box including relatively movable core forming elements, means for holding said elements together when said box is in position for ramming, and means for locking said box to said base.
  3. A core forming device comprising a base, a core forming box supported for rotation as a unit upon said base, said box including relatively immovable core forming elements, means on said base for holding said elements together when said box is in position for ramming, and means for locking said box to said base.
  4. A core forming device comprising a base, a core forming box supported for rotation upon said base, said box including relatively movable core forming elements, and cooperating wedge surfaces on said base and elements for holding said elements together when said box is in position for ramming, and means for locking said box to said base.
  5. A core forming device comprising a base, a core forming box supported for rotation from a ramming position to a core removal position on said base, said box including swingably supported core forming elements, and cooperating wedge surfaces on said base and elements for holding said elements together when said box is in its ramming position.
  6. A core forming device comprising a base, a core forming box supported for rotation from a ramming position to a core removal position on said base, said box including swingably supported core forming elements, cooperating wedge surfaces on said base and elements for holding said elements together when said box is in its ramming position, and means for locking said box to said base when in said ramming position.
  7. A core forming device comprising a base, a core forming box supported for rotation from a ramming position to a core removal position on said base, said box including swingably supported core forming elements, cooperating wedge surfaces on said base and elements for holding said elements together when said box is in its ramming position, means for locking said box to said base when in said ramming position, and means for initiating movement of rotation of said box upon release of said locking means.
  8. A core forming device comprising a base, a core forming box, said box including a core forming element pivoted to said base, core forming elements pivoted to said first named element, said box being adapted to be rotated about said first
  9. A core forming device comprising a base, a core forming box, said box including a core forming element pivoted to said base, core forming elements pivoted to said first named element, said box being adapted to be rotated about said first named element from ramming position to core removing position, and means for holding said elements together during said movement.
  10. A core forming device comprising a base, a core forming box, said box including a core forming element pivoted to said base, core forming elements pivoted to said first named element, said box being adapted to be rotated about said first named element from ramming position to core removing position, and means for holding said elements together when said box is in its ramming position.
  11. A core forming device comprising a base, a core forming box, said box including a core forming element pivoted to said base, core forming elements pivoted to said first named element, said box being adapted to be rotated about said first named element from ramming position to core removing position, and cooperating wedge surfaces on said base and elements for holding certain of said elements together when said box is in its ramming position.
  12. A core forming device comprising a base, a core forming box, said box including a core forming element pivoted to said base, core forming elements pivoted to said first named element, said box being adapted to be rotated about said first named element from ramming position to core removing position, cooperating wedge surfaces on said base and elements for holding certain of said elements together when said box is in its ramming position, and means for locking said box to said base when in said ramming position.
  13. A core forming device comprising a base, a core forming box, said box including a core forming element pivoted to said base, core forming elements pivoted to said first named element, said box being adapted to be rotated about the pivotal axis of said first named element from ramming position to core removing position, cooperating wedge surfaces on said base and elements for holding certain of said elements together when said box is in its ramming position, and means for locking said box to said base when in said ramming position.
  14. A core forming device comprising a base, a core forming box having core forming elements, means for hingedly connecting said elements, and means for hingedly supporting said box on said base.
  15. A core forming device comprising a base, a core forming box supported for rotation from a ramming position to a core removal position on said base, said box including swingably supported core forming elements, and means for rotating said box from its ramming position to its core removal position.
  16. A core forming device comprising a base, a core forming box swingably supported upon said base, and means for swinging said box into a plurality of positions.
  17. A core forming device comprising a base, a core forming box swingably supported upon

- said base, and fluid operated means for swinging said box into a plurality of positions.
18. A core forming device comprising a base, a core forming box swingably supported upon said base, and means associated with said base for swinging said box into a plurality of positions. 80
19. A core forming device comprising a base, a core forming box swingably supported upon said base, and a fluid operated piston associated with said box for swinging the same into a plurality of positions. 85
20. A core forming device comprising a base, a core forming box mounted for rotation on said base, said box including swingably supported core forming elements, and a fluid operated piston associated with one of said elements for rotating said box into a plurality of positions. 90
21. In a core forming device, the combination of a core forming box, a core carrier plate, and means extending through the core for holding said plate in association with said box. 95
22. In a core forming device, the combination of a core forming box, a core carrier plate, and magnetic means for holding said plate in association with said box. 100
23. In a core forming device, the combination of a core forming box, said box including a plurality of swingably associated core forming elements, a core carrier plate associated with one of said elements, and means for holding said plate in association with said element. 105
24. A core forming device comprising a base, a core forming box supported for rotation on said base and swingable from a ramming to a core removal position, said box having relatively movable core forming elements disposed to open when said box is in said core removal position. 110
25. A core forming device comprising a base, a core forming box including a plurality of relatively movable core forming elements, means for supporting said box on said base whereby the same is movable from a ramming to a core removal position, and means engageable by said box when swung from a core removal to a ramming position for holding said elements together for ramming. 115
26. A core forming device comprising a base, a core forming box including a plurality of relatively movable core forming elements, means for supporting said box on said base whereby the same is movable from a ramming to a core removal position, and means engageable by said box for moving certain of said elements into closed relation and to hold the same together for ramming. 120
27. A core forming device comprising a base, said base having a recess and a platform, a core forming box movably mounted on said base, said box being normally disposed in said recess when in a ramming position and movable onto said platform when in a core removal position. 125
28. A core forming device comprising a base, said base having a recess and a platform, a core forming box movably mounted on said base, said box being normally disposed in said recess when in a ramming position and movable onto said platform when in a core removal position, said box including relatively movable core forming elements disposed to open when said box is disposed on said platform. 130
29. A core forming device comprising a base, said base having a recess and a platform, a core forming box including relatively movable core forming elements movably mounted on said base and movable from a ramming to a core removal position, said box being received in said recess when in a ramming position and being movable onto said platform when in a core removal position, said element having a core forming portion adjacent one end thereof, means disposed in substantially normal relation to said element adjacent the other end thereof for pivoting supporting the other of said elements when said box is in a core removal position. 135
30. A core forming device comprising a base, said base having a recess and a platform, a core forming box including relatively movable core forming elements movably mounted on said base and movable from a ramming to a core removal position, said box being received in said recess when in a ramming position and being movable onto said platform when in a core removal position, said element having a core forming portion adjacent one end thereof, means disposed in substantially normal relation to said element adjacent the other end thereof for pivoting supporting the other of said elements when said box is in a core removal position. 140
31. A core forming device comprising a base, a core forming box including a plurality of relatively movable core forming elements, means for movably supporting one of said elements on said base whereby said box as a unit is movable from a ramming to a core removal position, said element having a core forming portion adjacent one end thereof, and means disposed in substantially normal relation to said element adjacent the other end thereof whereby the other of said elements are movable therewith. 145
32. A core forming device comprising a base, a core forming box including a plurality of relatively movable core forming elements, means for movably supporting one of said elements on said base whereby said box as a unit is movable from a ramming to a core removal position, said element having a core forming portion adjacent one end thereof, and means connected to said element adjacent the other end thereof and in substantially normal relation thereto for swingably supporting the other of said elements when in a core removal position. 150
33. A core forming device comprising a base, a core forming box including a plurality of relatively movable core forming elements, means for pivotally supporting one of said elements on said base whereby said box as a unit is swingable from a ramming to a core removal position, said element having a core forming portion adjacent one end thereof, means disposed in substantially normal relation to said element adjacent the other end thereof for pivotally supporting the other of said elements when said box is in a core removal position, and means engageable by said last-named elements for closing said box when the same is moved from a core removal to a ramming position and for holding said elements together when said box is in a ramming position. 155
34. A core forming device comprising a base, said base having a recess and a platform, a core forming box including a plurality of relatively movable core forming elements, means for swingably supporting one of said elements on said base whereby said box as a unit is movable from a ramming to a core removal position, said box being received in said recess when in a ramming position and being movable onto said platform when in a core removal position, said element having a core forming portion adjacent one end thereof, means disposed in substantially normal relation to said element adjacent the other end thereof for pivotally supporting the other of said elements, said elements being in normal closed position when said box is in a ramming position and being disposed to open only when said box is in a core removal position. 160

35. A core forming device comprising a base, said base having a recess and a platform, a core forming box including a plurality of relatively movable core forming elements, means for swingably supporting one of said elements on said base whereby said box as a unit is movable from a ramming to a core removal position, said box being received in said recess when in a ramming position and being movable onto said platform 10 when in a core removal position, said element having a core forming portion adjacent one end thereof, means disposed in substantially normal

relation to said element adjacent the other end thereof for pivotally supporting the other of said elements, said elements being in normal closed position when said box is in a ramming position and being disposed to open when said box is in a core removal position, and means engageable by said other elements for closing said box when the same is moved from a core removal to a ramming position and for holding said elements together when said box is in a ramming position. 80
